UNITED STATES PATENT OFFICE.

LOUIS C. SUMMERS, OF SHADY POINT, OKLAHOMA.

CULTIVATOR HOPPLE.

Application filed October 2, 1926. Serial No. 139,140.

The present invention relates to a hopple for cultivators and has for its prime object to provide an adjustable structure which may be used to advantage also in scraping cotton and in trashy ground.

Another important object of the invention lies in the provision of a device of this nature which is possessed of an exceedingly simple structure and which may be manufactured at a low cost, one which is strong and durable, easy to manipulate, thoroughly reliable and efficient in use, and otherwise well adapted for the purpose for which it is designed.

With the above and numerous other objects in view, as will appear as the description proceeds, the invention resides in certain novel features of construction, and in the combination and arrangement of parts as will be hereinafter more fully described and claimed.

In the drawing:

Figure 1 is a rear elevation of the device showing the same associated with a cultivator,

Fig. 2 is a front elevation of the device.

Referring to the drawing in detail, it will be seen that 5 denotes one side bar of the hopple having the upper end curved inwardly as at 6. The numeral 7 denotes the other bar which is shorter in length than the bar 5 and has the curved upper end 8.

The terminals of the curved ends 6 and 8 are bolted together as at 9. A cross bar 10 is bolted as at 11 to the bars 5 and 7 and is formed in two sections which overlap each other and have registering apertures 12 for receiving bolts 14. Thus the length of the cross bar 10 may be adjusted. An auxiliary bar 15 overlaps the lower end of the bar 7 and is bolted thereto as at 16 and 17. A stop 18 is bolted to the bar 7 as at 19 between the bolts 16 and 17. On the bottom terminal of the bar 5 and the auxiliary bar 15 there are pivoted pin plates 16 which are twisted at right angles between their ends. These pin plates are pivoted to the bar 5 and auxiliary bar 15 as at 17 and are adapted to be received in openings 20 provided in the cross beams of the cultivator indicated generally by the letter C in Fig. 1.

My improvement lies particularly in the joint 16-17 provided between the bar 7 and the auxiliary bar 15. When the parts are disposed as is shown in the drawing, the device is used as an ordinary cultivator

hopple. When it is desired to use the device in scraping cotton or in trashy ground, the bolt 17 is removed and then there is formed a hinged joint between the bar 7 and the bar 15 which permits either plow beam of the cultivator to be raised until auxiliary bar 15 comes in contact with the left-hand end of member 18. This permits either plow beam to be shaken so as to swing the plows or scrapers from any track and at the same time the plows are hoppled as with any ordinary hopple.

It is thought that the construction, utility, and operation of this invention will now be clearly understood by those skilled in this art without a more detailed description thereof. The present embodiment of the invention has been disclosed in detail merely by way of an example, since in actual practice it attains the features of advantage enumerated as desirable in the statement of the invention and the above description. It will be apparent that changes in the details of construction may be resorted to without departing from the spirit or the scope of the invention as hereinafter claimed or sacrificing any of its advantages.

Having thus described my invention what I claim as new is:

1. A cultivator hopple of the class described including, in combination, a relatively long bar having its upper end curved, a relatively short bar having its upper end curved, the extremities of the curves being pivotally bolted together, an extensible cross bar between the relatively long and relatively short bars, an auxiliary bar, a pair of bolts attaching the auxiliary bar to the relatively short bar, one of said bolts being removable to allow pivotal movement, a stop attached to the relatively short bar between the bolts attaching the auxiliary bar to the relatively short bar, and a pair of pin plates pivoted on the extremities of the relatively long bar and the auxiliary bar.

2. A cultivator hopple of the class described including, in combination, a relatively long bar having its upper end curved, a relatively short bar having its upper end curved, the extremities of the curves being pivotally bolted together, an extensible cross bar between the relatively long and relatively short bars, an auxiliary bar, a pair of bolts attaching the auxiliary bar to the relatively short bar, one of said bolts being removable to allow pivotal movement, a stop

attached to the relatively short bar between the bolts attaching the auxiliary bar to the relatively short bar, and a pair of pin plates pivoted on the extremities of the relatively long bar and the auxiliary bar, said pin plates being twisted intermediate their ends at right angles.

3. A cultivator hopple of the class described including, in combination, a relatively long bar having its upper end curved, a relatively short bar having its upper end curved, the extremities of the curves being pivotally bolted together, an extensible cross bar between the relatively long and relatively short bars, an auxiliary bar, a pair of

bolts attaching the auxiliary bar to the relatively short bar, one of said bolts being removable to allow pivotal movement, a stop attached to the relatively short bar between the bolts attaching the auxiliary bar to the relatively short bar, and a pair of pin plates pivoted on the extremities of the relatively long bar and the auxiliary bar, said pin plates being twisted intermediate their ends at right angles, the brace between the relatively short and long bars being adjustable and being formed in sections bolted together.

In testimony whereof I affix my signature.

LOUIS C. SUMMERS.
